UNITED STATES PATENT OFFICE

CHARLES BOSTICK HURD, OF SANTA ANA, CALIFORNIA

CUPBOARD LATCH

Application filed April 21, 1927. Serial No. 185,500.

This invention is of general application to door catches of the mortise type, but, is more particularly applicable to mortised catches having spring actuated bolts and knobs, or handles, and shanks for moving the bolts to unlatched positions.

An object of the invention is to provide an improvement in shank operated latches of the mortise type which involves few parts and is inexpensive and the installation of which involves only such adaptation of the door and jamb as may be accomplished solely by augers, or similar boring tools. One of the advantages aimed at is easy longitudinal 15 operation of the bolt by the turning of a knob.

Another object is to provide in a latch of this type a simple means for connecting the latch bolt with the knob-shank which means coacting with the latch casing serves as a lock 20 against door opening except by a rotation of the knob shank and which means also acts to hold the knob shank to the latch bolt during installation.

A feature of the invention is in the particular shaping of the several parts of the latch whereby their installation involves the making of receiving mortises, cavities and holes solely by boring tools.

Among the advantages is simplicity and 25 cheapness of construction and a minimum of time and effort in installation.

Other objects, advantages and features of invention may appear from the accompanying drawing, the subjoined detailed description 30 and the appended claims.

The accompanying drawing illustrates the invention.

Figure 1 is a longitudinal sectional elevation of a latch embodying my invention, as 35 installed in a door having its hinges at the right hand side, fragments only of the door and door jamb being shown.

Fig. 2 is a view similar to Fig. 1, showing the latch as installed in a door having its 40 hinges at the left hand side.

Fig. 3 is a vertical sectional elevation taken on the line x^3 , Fig. 1.

Fig. 4 is a plan view taken on the line x^4 , Fig. 1.

Fig. 5 is a perspective view of the latch.

barrel showing the bayonet slot for holding the knob-shank.

Fig. 6 is a view similar to Fig. 5 showing a bearing for the knob-shank.

Fig. 7 is a perspective view of the latch-bolt showing the cam faced recess for bolt movement by a knob.

Fig. 8 is a view similar to Fig. 7 showing a cut away for accommodating the knob-shank.

Fig. 9 is a perspective view of the keeper and striking plate.

A and B designate generally the door and door jamb, respectively, which are shown only fragmentarily in Figs. 1 and 3, and may 65 be of any conventional construction.

The catch proper comprises a casing 1, the body 2 of which is tubular, and constructed preferably from a length of cylindrical metal tubing, having its inner end closed, as 70 by an end 3, drawn or constructed as a metallic disc and brazed, or otherwise secured and extending nearly half way round the casing, at the end of the body. The casing has in the front side, at approximately its longitudinal center, a tappet way 4; and in the top side, a slot 5, open intermediate its ends to the tappet way 4 and terminating a short distance beyond each side of the tappet way, 75 forming therewith a bayonet slot, and said casing has a hole, or perforation 6, in the rear side, open to the tappet-way 4.

The latch bolt 7 is of substantially cylindrical shape, and has in its front side next its outer end a flat face 8 terminating at an outwardly extending shoulder 9 and the outer end of the bolt is bevelled to form the striking face 10. The bolt is provided at approximately its longitudinal center with a cam notch 11, the rear wall of which forms a cam 90 12 for bolt movement, and, in the bottom side of the bolt there is a cut-away 13 providing clearance for the bolt moving means.

Into the casing, there is first placed a compression spring 14, and the bolt is fitted in the casing with its notch 11 registering with the tappet-way 4 of the casing.

A flush-plate 15, of disc-shape and of greater diameter than the casing, is secured, as by brazing, to the casing end. As best 100

shown in Fig. 5, the flush plate has an opening 16 conformed to the flat faced portion of the bolt which is thereby held again rotation in the casing, with its notch 11 properly related to the tappet-way 4, and its shoulder 9 held by the flush plate to limited movement outwardly, beyond the casing.

The latch operating means comprises a shank 17 and a bolt throwing element or tappet 18, which is shown as a pin extended through and secured to the shank, to which a pull as the knob 19 is secured.

A keeper 20, constructed as a substantially circular open metal ring having an extension 21 is provided to serve as a striking plate for the bevel face 10 of the projecting end of the bolt.

The knob is secured to the shank as by a fitting 22, into which the base of the knob is seated, and from which fitting extends a sleeve 23 which is slipped over the shank. An escutcheon 24 is placed over the sleeve, next the fitting and the knob, shank and escutcheon held assembled by a pin 25 extended through the sleeve and shank, as best shown in Fig. 3.

To install the latch a shallow hole 26, to seat the flush plate 15, is bored in the edge of the door A, and central to such shallow hole, a relatively deep hole 27, to seat the casing, is bored, and a hole 28 is bored into the face of the door to intersect the hole 27 and to receive and accommodate the shank 17 and its element 18.

To install the keeper, a shallow hole 29, to seat the keeper, is bored in the face of the door jamb B and central to the shallow hole, a relatively deep hole 30, to receive the bolt end, is bored.

An advantage incident to the shaping of the several parts of my latch is that the latch may, by simple inversion of parts, be used either in a right or left hand swung, or hinged, door.

In Fig. 1, the latch is installed as in a right hand swung door, in which the bolt throwing element 18 is pointed upwardly, and the shank disposed beneath the bolt. By a simple end for end bodily inversion of the latch and bolt, and a placing of the shank above the bolt with its element pointed downwardly as shown in Fig. 2, the latch, without alteration may be installed in a left hand swung door.

By preference, and as shown, the bolt throwing element, namely the pin 18, is of such length to extend beyond the periphery of the bolt 7 and the casing 1 is provided with a longitudinally disposed slot 5 to accommodate the projected end of the pin, in any of its positions.

By reason of the slot 5 being open to the tappet-way 4, the pin may be readily introduced along with the shank 17, to its operating position through the tappet-way 4 and

into the slot 5. Upon manual release of the shank, after the pin has been introduced into the slot 5, the spring serves to advance the bolt and carry the pin forwardly in the slot 5, beyond the tappet-way 4 and thus the pin and slot 5 act as a means for releasably securing the bolt throwing means against displacement during the final installing steps, which includes the securing of the escutcheon 24.

I claim:—

1. A latch comprising a cylindrical tubular casing having a bayonet slot, a substantially cylindrical bolt slidably mounted in the casing, and having a notch in its side and a cut-away intersecting the notch, a shank for extension into said cut-away, a pin carried by the shank for engagement in said notch; and a spring for normally holding the bolt to a position seating said pin in the bayonet slot.

2. A latch comprising a cylindrical tubular casing, having a bayonet slot, a substantially cylindrical bolt having a transverse cut-away and a cam faced notch, a spring acting on the bolt to normally hold it in latched position, means for holding the bolt against rotation in the casing, a shank, and a pin carried by the shank for the throwing of the bolt and for engagement in the bayonet slot to form with the bolt and spring releasable means for securing the shank to the casing.

3. A latch comprising a cylindrical casing having a tappet way extending around one side and a slot extending along the casing and open to one end of the tappet way and extending on opposite sides thereof; a bolt in the casing and extending therealong and provided with a notch in one side and a cam way open to the notch and to said slot; a shank journaled in the casing and provided with a pin to operate as a tappet in the cam way and extending into the slot; said shank being adapted and arranged to be turned for the purpose of moving the bolt longitudinally.

In testimony whereof, I have hereunto set my hand at Los Angeles, California, this 16th day of April, 1927.

CHARLES BOSTICK HURD.
